SWEAT-BAND FOR HATS

Herman Wessel Roeloffzen, New York, N. Y.

Application January 5, 1934, Serial No. 705,303

5 Claims. (Cl. 2—182)

This invention relates to new and useful improvements in sweat-bands, and it has for its object to provide a medium or band of this kind, which in an infallible manner will protect the body of a hat, or cap, and more especially the lower circumference of the felt of the hat, against the damaging and devastating effect of perspiration.

The features making up the said protection are of a varied nature, as they reside not only in the materials employed and the relative arrangement of the latter, but also in the ingenious manner in which the said materials and protective means are secured to the body of the hat proper.

As the construction involved relative to this device is comparatively simple, and the materials used inexpensive, the cost of applying this protective means may be considered insignificant, especially in view of the very great extended period of time of useful wear that such protection would give to a hat.

The arrangement of elements in regard to this invention also contemplates the exchange of a sweat absorbing inlay or refill-member, whenever the latter is saturated with perspiration, thereby adding further durability to the features constituting the invention proper, and the life of a hat.

With the above and other objects in view, this invention consists of the novel features of construction, combination and arrangement of parts, hereinafter fully described, claimed and illustrated in the accompanying drawing forming part of this specification, and in which similar characters of reference indicate corresponding parts in all views, and in which:

Figure 1 illustrates the sweat band, constituting my invention, and showing the inside of the said sweat band, when the latter is unfolded, or open.

Figure 2 shows the sweat band, in part, folded, and ready for attachment to a hat; while

Figure 3 illustrates, in part, an absorbing inlay, or refill-member.

Referring more particularly to the drawing, 10 indicates a sweat band, or member, suitable for attachment to a hat, for instance by sewing, and made of cellophane, koda-pack, celluloid, bakelite, or any other material adaptable for such purpose.

Thus, the said material may also be leather, or it may be a material, embossed or plain and colored, to represent imitation leather.

The said sweat band has its one half or inner portion 11 attached to a hat, preferably by means

of sewing, in regard to which a line of stitches has been shown at 12.

The said portion 11 has further below said stitch-line 12 been formed with an embossed or raised bead-line 13, which has for its specific purpose to guard against that any perspiration or dampness should be able to reach the felt or the said stitch-line 12 from below, that is penetrate between the sweat band and the felt of the hat.

The sweat band will fold on the line 14; and the outer portion 15 is then secured to the inner half 11, by means of snap-fasteners 16. When in this folded position the longitudinal ends of the sweat band may be connected together by means of openings 17 and flaps 18, which in turn may be secured together by a clip 19, or the conventional piece of silk ribbon.

The outer portion 15 of the sweat band is provided with perforations 20, whereby to absorb the perspiration from the head of a person.

Within the folded sweat band 10, is in turn arranged a removable refill-member 21.

The said member 21 consists of two layers 22 and 23, of which the one layer 22 is of an absorbing material of any kind suitable, and facing the outer portion 15 of the sweat band with the perforations therein for the purpose of absorbing the perspiration from the latter, while the other layer 23 is of an impenetrable kind of material, such as cellophane, koda-pack, or the like, and serving to prevent the perspiration absorbed by the material 22 from going any farther towards, or from reaching the inner band portion 11, and subsequently in turn the felt of the hat.

The said layer 23 may for this purpose be formed with an upper slightly outwardly projecting flange, or rim portion 24.

The detachable absorbing, or refill-member 21, has the layers 23 and 22, constituting the former, secured together in any suitable manner, as by glueing, or sewing, and the said absorber 21 is held in a fixed position between the folded sections 11 and 15, by means of the snap-fasteners 16, as it rests at the bottom fold of 45 the two sections 11 and 15.

Thus it appears obvious that the said absorber, or refill-member 21, will prevent any perspiration from reaching the stitch-line 12, where the holes, made by the needle, and the thread, 50 in said holes, respectively, would otherwise, if not prevented by the said refill-member, be instrumental in carrying the perspiration to the outside felt of the hat and the hat band thereon.

It is obvious that changes may be made in the 55

form, construction and arrangement of the several parts, as shown, within the scope of the appended claims, without departing from the spirit of the invention, and I do not therefore wish to limit myself to the construction and arrangement shown and described herein.

Having thus described my invention, what I claim as new and desire to secure by Letters Patent of the United States, is:—

10 I claim:

1. In a device of the class described, a sweat band folded upon itself, and having one side thereof formed with perforations, and the other side with a raised bead-line to guard against the perspiration penetrating in an upward direction, a refill-member, comprising a layer of an absorbent material facing the perforated side of the sweat band, and a second layer of an impenetrable material facing the other side of the sweat band for the purpose of preventing the perspiration from reaching the felt of a hat by means of the holes and threads of the stitch-line securing the sweat band to a hat.

2. A felt hat in combination with a sweat band, comprising a member of a thin and pliable material, folded upon itself to form two flaps of a substantially even width, the inner one of said flaps being provided near its lower edge with a raised bead-line and being secured to the felt of the hat by means of stitches, the line of said stitches lying above, or higher than the said bead-line, the outer flap being formed with perforations therein, a refill-member disposed between said flaps and consisting of a plurality of layers, the one of the latter facing the flap with the perforations therein being of an absorbing material, and the layer nearest to the inner flap being of an impenetrable material, substantially as shown and described.

3. A felt hat in combination with a sweat band, comprising a member of a thin and pliable material, folded upon itself to form two flaps of a

substantially even width, the inner one of said flaps being provided near its lower edge with a raised bead-line and being secured to the felt of the hat by means of stitches, the line of said stitches lying above, or higher than, the said bead-line, the outer flap being formed with perforations therein, a refill-member disposed between the said flaps, and comprising two layers of materials integrally secured together, one of the said layers, facing the flap having the perforations therein, being of an absorbent material, and the other layer facing the inner flap being of an impenetrable material, thereby protecting the stitch-line against perspiration.

4. A felt hat in combination with a sweat band, comprising a member of a thin and pliable material, folded upon itself to form two flaps of a substantially even width, the inner one of said flaps being provided near its lower edge with a raised bead-line and being secured to the felt of the hat by means of stitches, the line of said stitches lying above, or higher than, the said bead-line, the outer flap being formed with perforations therein, a refill-member disposed between the said flaps, and comprising two layers of material integrally secured together, one of the said layers, facing the flap having the perforations therein, being of an absorbing material, and the other layer facing the inner flap projecting somewhat above the first layer, to form a flange, slightly outwardly bent, and consisting of an impenetrable material, thereby protecting the stitch-line against perspiration, substantially as shown and described.

5. In a device of the class described, a sweat band folded upon itself, and having one side thereof formed with perforations, and the other side with a raised bead-line to guard against the perspiration penetrating in an upward direction, and a filler of an absorbent material mounted in the folds of said sweat band.

HERMAN WESSEL ROELOFFZEN.
